UNITED STATES PATENT OFFICE.

LARS A. LARSON, OF ELGIN, ILLINOIS.

COMBINED LEVELER AND WEED-GATHERER FOR CULTIVATORS.

1,061,387.

Specification of Letters Patent.

Patented May 13, 1913.

Application filed December 14, 1910. Serial No. 597,267.

To all whom it may concern:

Be it known that I, LARS A. LARSON, a citizen of the United States, and a resident of Elgin, in the county of Kane and State 5 of Illinois, have invented certain new and useful Improvements in a Combined Leveler and Weed-Gatherer for Cultivators, of which the following, when taken in connection with the drawing accompanying and 10 forming a part hereof, is a full and complete description, sufficient to enable those skilled in the art to which it pertains to understand, make, and use the same.

This invention relates to a device which is 15 removably attached to cultivators; and the object of the invention is to obtain means whereby as a cultivator is drawn over a field the weeds which are uprooted will be gathered and carried along with the device until 20 the same are deposited by the operator of the cultivator; and further, to obtain means whereby the dirt which is disturbed by the cultivator will be leveled and left free from the weeds which have been removed there- 25 from.

A further object of the invention is to obtain a device of the character named which will be simple in construction, easily removed from the cultivator to which it is attached, easily set back on said cultivator and quickly adjusted for the desired use thereof, durable, not likely to get out of order, and readily manipulated by the operator of the cultivator.

35 In the drawing referred to Figure 1 is a top plan view of the principal part of the frame of a cultivator removed from the axle, tongue and seat bar, with a device embodying this invention attached thereto. Fig. 2 40 is a rear elevation of a cultivator with a device embodying this invention attached thereto. Fig. 3 is a side elevation of a portion of a cultivator, with the device embodying the invention attached thereto, and Fig. 45 4 is a side elevation of the parts of the frames which are illustrated in Fig. 1, with the weed gathering frame adjustably raised.

50 A reference letter applied to a given part is used to designate said part throughout the several figures of the drawing wherever the same appears.

A is the frame of a cultivator, and B, B, are the shovels of the cultivator.

55 C is the axle and D, D, the carrying wheels of the cultivator.

E, E, are the frames of a device embodying this invention.

F is a curved metal plate, which is bolted to the forward end of a frame of the device and which is engageable, (by means of the 60 curved end,) with the cross bar of cultivator frame A.

G is a bar which is rigidly attached to frame E, and extended out from said frame to a point above or over one of the members 65 of frame A, and H is a screw threaded bolt which is vertically mounted in bar G, so that the lower end thereof rests on the frame A, or on one of the members of said frame. Adjustability of the bolt H in bar G is ob- 70 tained by cutting a screw thread thereon and making a correspondingly screw threaded hole in said bar G; and said bolt is retained in an adjusted position by means of the set nut *h*. As the bolt H is screwed down into 75 the bar G the rear end of the frame E is raised (as is illustrated in Fig. 4), the forward end of said frame remaining hooked to one of the members of frame A, as described.

I, I, are shovels attached to the rear end 80 of the frame E. These shovels I are, therefore, raised or lowered relative to the shovels B, B, of the cultivator by the adjustment of the bolt H.

J is a handle attached to frame E, and by 85 means of which the operator of the cultivator can, at any time, raise the frame E to bring the shovels I, out of the ground.

When the cultivator frame A is raised by the operator, as in turning around at the 90 ends of rows, the frames E of this device are raised therewith, by means of the bar G and bolt H, (because the lower end of said bolt rests on frame A), and at other times the frame of this device may be raised by the 95 handle J, as the bolt H is then simply lifted from said frame A. It will be observed that the shovels B, B, are broader than the shovels I, I, and that said shovels I are so 100 disposed as to run between the furrows which are raised by the shovels B, but back of the same. It will also be noticed that although I show two frames E said frames may be joined together and the making of two frames is for the purpose of lessening the labor of lifting them to discharge the weeds gathered thereby and to permit more frequent discharge of the weeds on one side of the cultivator than on the other, when desired.

The operation of the device is,—as the cultivator is driven over a field and the land turned into furrows with the weeds in a substantially horizontal position the teeth or shovels I, I, cut through said furrows, to a depth which is determined by the adjustment of the frames E, and throw the dirt of said furrows back onto the hollow left by the shovels B, and also gather the weeds and 10 carry them along with the device. Whenever the operator desires he raises the handles J and the weeds are thereby deposited from the shovels I.

When the device is not to be used it is 15 disengaged from the member of the cultivator frame and removed from said cultivator frame.

I claim;

1. A cultivator frame provided with 20 shovels and with a seat, in combination with an additional frame, said additional frame provided with means to removably attach it to the cultivator frame, shovels on said additional frame, said shovels alined in 25 a row and positioned to be back of and between the first named shovels when said frames are attached together, means to adjustably raise the rear end of the additional frame and means to maintain said additional frame in an adjusted position, means to change said additional frame from an 30

operative to an inoperative position independently of the operative position of the cultivator frame, the connection between the frames being such that when the cultivator 35 frame is raised the additional frame is also raised.

2. A cultivator frame provided with a horizontal bar, shovels on said frame, an additional frame, a curved plate attached to 40 the forward end of the additional frame and removably attachable to the horizontal bar, said additional frame movable from an operative to an inoperative position independently of the operative position of the 45 cultivator frame, a vertically mounted screw threaded bolt in the additional frame, said bolt positioned so that the lower end thereof rests on the cultivator frame, a lock nut on said bolt, shovels on said additional 50 frame and a handle to said additional frame, the said shovels alined in a row and positioned so that the shovels on the additional frame are behind and between the shovels on the cultivator frame. 55

Signed at Elgin, Illinois, this 28th day of November, 1910.

LARS A. LARSON.

In the presence of—

FRANK W. SHEPHERD,
CLARENCE JENSEN.
